UNITED STATES PATENT OFFICE

2,391,628

STEAM GENERATOR

Thad C. Johnson, Clinton, S. C.

Application April 20, 1944, Serial No. 531,944

10 Claims. (Cl. 122—448)

My invention relates to steam generators, for heating, power or general uses.

An important object of the invention is to provide apparatus of the above mentioned character which will practically instantaneously generate steam, under positive control with respect to retort temperature, pressure and introduction of water.

A further object of the invention is to provide apparatus of the above mentioned character having the maximum degree of safety in operation.

A further object of the invention is to provide a boiler of the instantaneous or flash type wherein the water is introduced into the header or retort only as required and then only when conditions are right for instantaneous steam generation and further only when the pressure within the apparatus is below a selected high danger point.

A further object of the invention is to provide apparatus of the above mentioned character having the maximum speed and economy in operation which results from heating a small mass of the furnace unit and only the small quantity of water which is instantaneously converted into steam.

A further object of the invention is to provide apparatus of the above mentioned character which is simple in construction, easy to control and flexible in operation.

A further object of the invention is to provide apparatus of the above mentioned character which is in the form of a compact unit, allowing the same to be installed in a small space, thus eliminating the need for the usual basement for receiving the conventional heating plant.

Other objects and advantages of the invention will be apparent during the course of the following description.

In the accompanying drawings forming a part of this application and in which like numerals are employed to designate like parts throughout the same,

Figure 1 is a side elevation, partly diagrammatic, of apparatus embodying my invention,

Figure 2 is a vertical longitudinal section taken on line 2—2 of Figure 3,

Figure 3 is a horizontal section taken on line 3—3 of Figure 2,

Figure 4 is a front end elevation of the boiler,

Figure 5 is a transverse vertical section taken on line 5—5 of Figure 2,

Figure 6 is a side elevation of the high temperature bulb, and associated elements, the parts being shown partly diagrammatically,

Figure 7 is a side elevation of the low temperature bulb, and associated elements, the parts being shown partly diagrammatically, and

Figure 8 is a side elevation of a high pressure opening switch, and associated elements, the parts being shown partly diagrammatically.

In the drawings, wherein for the purpose of illustration is shown a preferred embodiment of my invention, the numeral 10 designates a casing 10 of the boiler, which may be formed of refractory material, such as fire brick, and having an exterior covering 11 of heat insulating material. The casing is provided in its bottom with a transverse bridge 12 and in its front end has an opening 13. At its top and near its rear end, the casing has a smoke hood or coupling 14 for the escape of products of combustion and this coupling 14 is connected with the usual stack pipe 15. The casing 10 is also provided with vertically inclined baffles 16, secured to its sides.

Extending centrally and longitudinally within the casing 10 is a lower header 17, which is preferably cylindrical. The header is horizontally arranged and the forward end of the header 17 is covered by a head 18 and this forward end is supported in a recess 19, formed in the front end of the casing 10. The rear end of the casing 10 has an opening 20, and the header 17 extends through this opening 20 to the exterior of the casing. The rear end of the header 17 is open and is connected with a coupling 21, connected with a pipe 22, which discharges into a float trap 23. This float trap discharges into a pipe 24. The numeral 25 designates an upper header, which is preferably cylindrical and extends centrally and longitudinally within the casing 10, above and spaced from the lower header 17 and preferably parallel with the lower header and in alignment therewith. The opposite ends of the upper header are closed by heads 26. The baffles 16 are arranged upon opposite sides of the headers 17 and 25 and are spaced therefrom, and cause the heated gases and products of combustion, traveling rearwardly within the casing, to pass in close proximity to the headers. The lower ends of the baffles 16 are arranged at an elevation above the top of the bridge 12, as shown. The lower header 17 has vertical tubes 27 connected with its top portion and these vertical tubes are connected with the bottom portion of the upper header 25. The tubes 27 place the headers in communication with each other and these tubes are spaced longitudinally of the headers, as shown. A pipe 28 is connected with the upper header 25, preferably near its front end

and this pipe extends through the top of the casing 10, and is connected with a pressure gage 29, and a branch pipe 30. Connected with the header 25, near its rear end, is a steam main or outlet pipe 31, equipped with a pressure relief valve 32.

The steam main 31 may be connected with a steam supply pipe 33, extending to a vertical pipe 34. The pipe 33 has an adjustable back pressure valve 35 connected therein. Inlet pipes 36, which may be equipped with valves 37, are connected with radiators 38 to supply steam thereto and these radiators have outlet pipes 39, connected with a steam return pipe 40, which is connected with the vertical pipe 34. The vertical pipe 34 is connected at its lower end with a pipe 41, leading into a condenser tank 42, and connected with the top of a condenser coil 43, the lower end of which is connected with a vertical pipe 44, provided at its upper end with a down-turned outlet 45, arranged above the water level within the tank 42. A cold water supply pipe 44' leads into the tank 42 and has its lower end 45 discharging into the tank near its bottom. The pipe 44' is equipped with a float controlled ball-cock or valve 46, which maintains a constant water level and discharges the cold water into the bottom of the tank 42. The numeral 46' designates a drain pipe having a vertical portion 47, passing through the bottom of the tank 42 and having its upper intake end arranged near or at the water level. The vertical portion 47 is equipped with a thermostatically operated valve 48, arranged near the bottom of the tank 42. The valve 48 is closed as long as the water within the tank 42 is sufficiently cold to condense the steam within the coil 43 but when this water becomes too hot for this purpose, valve 48 automatically opens, draining the water from the tank 42 through the valve 48 and the vertical portion 47 beneath the valve 48. This will lower the level of the water within the tank 42, whereby ball-cock or valve 46 will open and cold water will be supplied in the tank 42, and when the temperature of the water within the tank 42 is again suitably lowered, valve 48 closes, and the level of the water within the tank 42 is restored. The pipe 24 is connected with the pipe 41, as shown. A water jacket 49 may surround a portion of the vertical pipe 34, and this water jacket has upper and lower pipes 50 and 51, leading into a hot water storage tank 52, as shown. The heat within the pipe 34 is therefore employed to heat the water within the tank 52.

At the forward end of the lower header 17 is a horizontal tube 53, extending to the exterior of the casing 10 and leading into the header 17. This tube receives and has screw-threaded engagement, at 54, with a water spraying device or nozzle 55, having an adjustable needle valve 56, for controlling the fineness of the spray. The nozzle 55 is preferably arranged concentrically of the header 17 and projects into its forward end. A pipe 57 is connected with the nozzle 55 and leads to the outlet side of a rotary pump 58, the inlet side of which is connected with a pipe 59, which leads into the lower portion of the tank 42, below the water level. The pump 58 is driven by a motor 60.

The numeral 61 designates an oil burner, driven by a motor 62, and having a nozzle 63, discharging into the firebox or lower portion of the casing, in advance of the bridge 12, and the nozzle 63 extends through the opening 13. An electrically operated stoker, or a gas burner may

be used, if desired, and I contemplate using any form of automatic heating device.

Disposed upon one side of the lower header 17 is a tubular housing 64, having its opposite ends closed. This tubular housing is in thermal contact with the header 17 and may be attached thereto by welding or the like. Arranged within the tubular housing 64 is a low temperature bulb 65, containing an expansible fluid. A pipe 66 is connected with the bulb 65 and passes to a pressure operated device 66'. This pressure operated device includes a casing 67' and a flexible diaphragm 68', connected with a rod 69' and moved downwardly by a spring 70', the tension of which may be adjusted. The numeral 67 designates a low temperature opening switch, including a blade 71', to engage with terminals 72', connected in the wire 68. This wire is connected with one terminal of the pump motor 60, the other terminal of which is connected with a wire 69. When the lower header 17 is suitably heated so that it will instantaneously convert water sprayed therein into steam, the fluid within the bulb 65 is expanded, and will act upon the diaphragm 68', and shift the blade 71' into engagement with terminals 72', whereby the circuit is closed at the switch 67 and the pump motor 60 driven, provided the pump motor circuit is closed at other points to meet the remaining conditions. However, should the lower header 17 not be sufficiently heated, then the action of the spring 70' would overcome the action of the fluid within the bulb 65 upon the diaphragm 68' and blade 71' would disengage terminals 72'. The switch 67 therefore opens upon the low temperature of the header 17. Disposed upon the opposite side of the header 17 is a horizontal tubular housing 73, having its opposite ends closed. This housing is in thermal contact with the header 17 and is welded to the same. Arranged within the tubular housing 73 is a high temperature bulb 74, in thermal contact with the housing and containing an expansible fluid. The high temperature bulb is connected with a pipe 75 which leads to a pressure operated device 76' of a high temperature opening switch 76. The pressure operated device 76' includes a casing 77', having a flexible diaphragm 78' therein, which is moved downwardly by a spring 79'. The diaphragm 78' has connection with a rod 80', connected with a blade 81', to engage terminals 82', connected with a wire 77a. One end of the wire 77a is connected with the wire 68 at 78, while its opposite end is connected with one terminal of the burner motor 62, the other terminal of which is connected with a wire 79, connected with the wire 69. The switch 76 is a high temperature opening switch and remains closed until the temperature of the header 17 reaches or exceeds the high danger point, at which time the fluid within the tube 74 expands sufficiently to overcome the action of the spring 79' and move blade 81' out of engagement with terminals 82', whereby the switch 76 is opened and the burner motor 62 stopped.

The numeral 77 designates a high pressure opening switch, including a blade 77' to engage terminals 78', connected in wires 78a and 79a. The blade 77' is connected with a rod 79', secured to the flexible diaphragm 80', mounted in a casing 81'. This diaphragm 80' is moved downwardly by a spring 82', the tension of which may be adjusted. The pipe 30 leads into the casing 81'. The spring 82' normally holds the switch 77 closed, but when the pressure within the upper header exceeds or reaches the high danger point,

this pressure will raise the diaphragm 80' and shift blade 77' out of engagement with terminals 78'. Wires 80 and 81 are connected with a temperature control thermostatic switch 82, arranged in a room or the like. The wire 81 is connected with the wire 79, wire 78 is connected with wire 68, and wire 69 is connected with wire 72, and wire 80 is connected with wire 71.

The operation of the apparatus is as follows: When the thermostat 82 calls for heat, it closes the circuit at that point. Since the pressure within the headers 17 and 25 is not now above or at the high danger point, the high pressure opening switch 77 is closed, and since the header 17 is not now heated at or above a predetermined temperature, the high temperature opening switch 76 is closed. Assuming that the header 17 has not as yet been heated to a sufficiently high temperature to instantaneously vaporize the water injected into the same, then the low temperature opening switch 67 is open. A circuit is therefore closed for driving the burner motor. In this closed circuit, current passes through wire 71, wire 80, thermostat 82, wire 81, wire 79a, switch 77, wire 78a, wire 68, wire 77a, switch 76, one terminal of motor 62, wire 79, wire 69 and back to the wire 72. The burner is therefore operated and the lower header 17 heated, but the pump motor 60 has not been operated, since switch 67 was open. When the lower header 17 is heated sufficiently for instantaneously vaporizing the water sprayed therein, then the fluid within the lower temperature bulb 65 will expand sufficiently to close the lower temperature opening switch 67 and a circuit will be closed for driving the pump motor 60. In this circuit, current will pass through wire 68, low temperature opening switch 67, one terminal of pump motor 60, and through the wire 69. When the pump motor is set into operation, the water will be fed to the nozzle 55, which will continuously spray the same into the lower header 17. The fineness of the spray may be regulated by adjustment of the needle valve 56. The burner motor 62 and the pump motor 60 are now both operating at the same time, since the lower header is at or above the lower operating temperature and below the high danger temperature, any suitable number of degrees being allowed between these extremes. Should the temperature of the lower header 17 rise to or above the high danger point, the fluid within the high temperature bulb 74 will expand sufficiently to open the high temperature opening switch 76, thus stopping the operation of the burner motor 62, while the pump motor 60 would continue to operate. Should the temperature of the header 17 drop below the point for instantaneously vaporizing water sprayed within the header, then the fluid within the low temperature bulb 65 would not be expanded sufficiently to retain the low temperature switch 67 closed, and this switch would open, and the pump motor would stop, although the burner motor might be driving. As soon as the action of the burner brings the header 17 up to the selected high temperature to instantaneously vaporize the water, then the pump motor 60 is again set into action by the closing of the low temperature opening switch 67. It is thus seen that as long as the temperature of the header 17 is within selected limits that both motors 62 and 60 may be operated, but when this temperature reaches or exceeds the high danger point, the high temperature opening switch 76 will open and stop the motor 62 while the motor 60 continues to

operate, and when the temperature of the header 17 is below the point to instantaneously vaporize the water, the low temperature opening switch will open and stop the motor 60 while the motor 62 continues to operate. However, should the pressure within the headers 17 and 25 rise to or above the danger point, then the high pressure opening switch 77 will open, and both motors 60 and 62 are stopped. The rheostat 82 automatically closes and opens the circuit, stopping both motors 60 and 62, if both are operating at that time, or stopping one motor if only one is operated.

Any water which may accumulate in the header 17 from condensation is fed to the trap 23 and returned by the pipe 24 to the pipe 41. As soon as the water is sprayed into the header 17, it is converted into steam and passes upwardly into and through the tubes 27 to the upper header 25. The upper header and tubes serve as a superheater. The steam then passes through the pipe 31, and through the pipe 33 to the several radiators and is returned to the vertical pipe 34. The returned steam enters the coil 43 and is condensed and discharged from the end 45 into the tank 42. The pump 58 withdraws the water from the tank 42 and feeds it to the nozzle 55. The level of the water within the tank 42 is maintained constant by the action of the valve 46, and the temperature of the water is regulated by the valve 48. The back pressure valve 35 holds the pressure up to a predetermined point, when the unit is operated, and this back pressure valve opens when the pressure within the unit arises above the pressure necessary to open the switch 77. Ordinarily, the pressure will not get this high, as it would be limited by the opening of the switch 77. However, the opening of the back pressure valve under these conditions, would take care of an overriding pressure that might result from any unevaporated water or saturated steam left in the retort 17 when the pressure switch 77 opens the circuit.

Instead of employing a rotary pump to feed the water to the nozzle 55, I may use a solenoid operated valve and supply the water to the valve under suitable pressure. The solenoid would be connected in the wire 68.

While I have shown a boiler unit including a single upper header and a single lower header, yet I may use a boiler unit having a plurality of upper headers and a plurality of lower headers. While I have shown only one boiler unit as a source of steam, yet I may employ any number of boiler units. While I have shown the boiler unit as supplying steam to radiators for heating purposes, yet the unit or units may be employed for supplying steam for any other purpose. In power applications, the temperature control 82 would be eliminated and the pressure limit switch 77 would be changed to one of the differential type, having a low pressure cut in and a higher pressure cut out point. The setting of these points would be determined by the pressure desired for the system.

It is to be understood that the form of my invention herewith shown and described is to be taken as a preferred example of the same, and that various changes in the shape, size, and arrangement of parts may be resorted to without departing from the spirit of my invention or the scope of the subjoined claims.

Having thus described my invention, what I claim is:

1. In a steam generator, a casing, a lower head-

er within the casing, an upper header within the casing, tubes connecting the headers, a nozzle for supplying water into the lower header, means to supply water to the nozzle, means for controlling the operation of the water supply means and including a low temperature opening switch, pressure operated means connected with the switch, a bulb arranged within the casing adjacent to the lower header for holding an expansible fluid and connected with the pressure operated means, a device for heating the lower header within the casing, means for operating the heating device, a high temperature opening switch for stopping the heating device operating means, pressure operated means connected with the high temperature opening switch, and a bulb arranged within the casing adjacent to the lower header for holding an expansible fluid and connected with the last named pressure operated means.

2. In a steam generator, a casing, a lower header within the casing, an upper header within the casing, tubes connecting the headers, a nozzle for supplying water into the lower header, means for heating the lower header, means for supplying water to the nozzle and having its operation automatically stopped when the temperature of the lower header is reduced so that it will not substantially instantaneously vaporize the water and including a bulb arranged adjacent to the lower header, and means for automatically stopping the operation of the heating means when the temperature of the lower header reaches or passes a high danger point and including a bulb arranged adjacent to the lower header.

3. In a steam generator, a casing, a lower header within the casing, an upper header within the casing, tubes connecting the headers, a nozzle for supplying water into the lower header, means for heating the lower header, means for supplying water to the nozzle and having its operation automatically stopped when the temperature of the lower header is reduced so that it will not substantially instantaneously vaporize the water and including a bulb arranged adjacent to the lower header, means for automatically stopping the operation of the heating means when the temperature of the lower header reaches or passes a high danger point and including a bulb arranged adjacent to the lower header, and means for stopping the operation of the water supply means and the heating means when the pressure within the headers reaches or passes the high danger point.

4. In a steam generator, a casing, a lower header within the casing, an upper header within the casing, tubes connecting the headers, a nozzle for supplying water into the lower header, means for heating the lower header, means for supplying water to the nozzle including an electrical device, a circuit connected with the electrical device, a switch biased to open and connected in the circuit, a pressure operated device to close the switch and including a bulb arranged adjacent to the lower header, an electrical device to operate the heating means, a circuit connected with the last-named electrical device, a switch biased to close and connected in the last-named circuit, and a pressure operated device to open the last-named switch and including a bulb arranged adjacent to the lower header.

5. In a steam generator, a casing, a lower header within the casing, an upper header within the casing, tubes connecting the headers, a nozzle for supplying water into the lower header, means for heating the lower header, means for supplying water to the nozzle including an electrical device,

a circuit connected with the electrical device, a switch biased to open and connected in the circuit, a pressure operated device to close the switch and including a bulb arranged adjacent to the lower header, an electrical device to operate the heating means, a circuit connected with the last-named electrical device, a switch biased to close and connected in the last-named circuit, a pressure operated device to open the last-named switch and including a bulb arranged adjacent to the lower header, a switch biased to close for controlling the supply of current to the circuits, and a pressure operated device to open the last-named switch and including a pipe in communication with the upper header.

6. In apparatus of the character described, a casing, a header within the casing, means to heat the header, a nozzle to supply water into the header, a condenser tank, a pump to withdraw water from the condenser tank and supply the same to the nozzle, means for receiving steam from the header, a return pipe connected with the discharge side of the means, a condenser coil within the tank below the water level thereof and discharging into the tank and connected with the return pipe, a water trap connected with the header and discharging into the condenser coil, float control means to supply cold water into the tank, and means to withdraw water from the tank when the temperature of the water rises to a selected degree.

7. In a steam generator, a casing, a boiler element arranged within the casing, a nozzle for spraying water into the boiler element, a device for heating the boiler element, means for supplying water to the nozzle and having its operation automatically stopped when the temperature of the boiler element is reduced so that it will not substantially instantaneously vaporize the water, and means for operating the heating device and having its operation automatically stopped when the temperature of the boiler element reaches or passes a high danger point.

8. In a steam generator, a casing, a boiler element arranged within the casing, steam outlet means for the boiler element, a nozzle for spraying water into the boiler element, a device to supply water to the nozzle, a heating device for the boiler element, and means to cause the water supply device and the heating device to operate at the same time, said means including a device to automatically stop the operation of the water supply device when the temperature of the boiler element is reduced so that it will not substantially instantaneously vaporize the water, and a device to automatically stop the operation of the heating device when the temperature of the boiler element reaches or passes a danger point.

9. In a steam generator, a casing, a boiler element arranged within the casing, steam outlet means for the boiler element, a nozzle for spraying water into the boiler element, a device to supply water to the nozzle, a heating device for the boiler element, and means to cause the water supply device and the heating device to operate at the same time, said means including a pressure operated device to automatically stop the operation of the water supply device when the temperature of the boiler element is reduced so that it will not substantially simultaneously vaporize the water and including a bulb arranged adjacent to the boiler element, and a pressure operated device to automatically stop the operation of the heating device when the temperature of the boiler element reaches or passes a danger

point and including a bulb arranged adjacent to the boiler element.

10. In a steam generator, a casing, a boiler element arranged within the casing, steam outlet means for the boiler element including a back pressure valve connected therein, a nozzle for spraying water into the boiler element, a device to supply water to the nozzle, a heating device for the boiler element, and means to cause the water supply device and the heating device to operate at the same time, said means including a pressure operated device to automatically stop the operation of the water supply device when the temperature of the boiler element is reduced so that it will not substantially simultaneously vaporize the water and including a bulb arranged

5 adjacent to the boiler element, and a pressure operated device to automatically stop the operation of the heating device when the temperature of the boiler element reaches or passes the danger point and including a bulb arranged adjacent to the boiler element, and pressure operated means having communication with the interior of the boiler element to automatically stop both the water supply device and the heating device when the pressure within the boiler element reaches or passes the high danger point, the back pressure valve opening at a pressure above that necessary to operate the last-named pressure operated means.

THAD C. JOHNSON.
